UNITED STATES PATENT OFFICE.

JOHN H. ROBERTSON, OF NEW YORK, N. Y.

ROAD-BED CONSTRUCTION.

SPECIFICATION forming part of Letters Patent No. 611,820, dated October 4, 1898.

Application filed March 30, 1896. Serial No. 585,352. (No model.)

To all whom it may concern:

Be it known that I, JOHN H. ROBERTSON, of the city and county of New York, in the State of New York, have invented a new and 5 useful Improvement in Road-Bed Construction, of which the following is a specification.

My invention relates to an improvement in road-bed construction, and more particularly to road-bed construction adapted for an underground trolley. In conduits for containing the power-transmitting wires, more particularly in climates where the changes in temperature are considerable and where the road-bed is disturbed by freezing and thawing, great annoyance is caused by the narrowing of the slot through which the trolley-arm extends.

My present invention has for its object a structure which will admit of forming the 20 walls of the conduit of comparatively light material and at the same time provide for holding them so firmly in position as to prevent any liability of the narrowing of the slots under the abnormal conditions of the 25 road-bed and at the same time keep the interior of the conduit free from objectionable obstruction.

A practical embodiment of my invention is represented in the accompanying drawings, 30 in which—

Figure 1 represents a transverse vertical section through a double-track road-bed and the conduits for carrying the power-transmitting wires, and Fig. 2 is a top plan view 35 of a portion of the road-bed.

The two tracks are denoted, respectively, by A and A', the rails of the track A being denoted by B B' and the rails of the track A' being denoted by b b'.

40 The conduits containing the underground wires are denoted, respectively, by C and C', the conduit C being located at the side and beyond the confines of the track A and the conduit C' at the side and beyond the 45 confines of the track A'. The conduits C C' are built in the space which is commonly left between the inner rails of the tracks of a double-track road and as near the adjacent or inner rails of the two tracks as is consistent 50 with room for gaining access to the exterior walls of the conduits. The conduits are

formed of side plates c c' of suitable lengths to be conveniently handled and having their upper portions slightly inclined toward each other, the bottom plate c², bolted to the lower 55 edges of the side plates, and slot-irons D D', bolted to the top horizontally-turned flanges of the side plates and provided with depending flanges d d', which extend downwardly within the mouth of the conduit and form 60 between them the slot along which the trolley-arm E of the car or other vehicle extends.

The conduits C C' are built upon beds F F', of cement or other suitable substance which is not liable to deteriorate or become broken 65 or otherwise disturbed and which at the same time will form a suitable support for embedding therein a nest of pipes or casings G for carrying the supply-wires to furnish the upper transmitting-wires with the required 70 amount of electricity at suitable intervals. The conduits are placed at such a depth as to bring the upper faces of the slot-irons D D' slightly below the general surface of the road-bed, which is here shown as formed of 75 paving-blocks H.

The rails B B' b b' rest upon ties I I', which are preferably embedded in what is known as "grout," (indicated at K,) and the interstices between the paving-blocks are filled 80 with sand, (indicated by L.)

The walls of the conduits are held in fixed relation to each other by means of tie plates and bars, arranged as follows:

Between the two conduits there is a deep 85 tie-plate M, the ends of which are provided with flanges m m', turned at an angle to the body of the plate and slanted to conform with the inclined position of the upper portions of the side walls of the conduits, to which they 90 are bolted by bolts m². This plate serves to hold the slot-irons on the adjacent walls of the conduits in fixed relation relative to each other. Shorter tie-plates N N', preferably having a depth corresponding to the depth of 95 the tie-plate M and having flanges at their end turned in a manner similar to the flanges on the plate M, are fitted to the spaces intervening between the rails B' b and the walls of the conduits adjacent thereto and are bolted 100 securely to the webs of the rails and to the walls of the conduits. This serves to hold

the opposite walls of the conduits, and hence the slot-irons connected therewith, in fixed relation to the track-rails adjacent thereto, and any movement of the wall of the conduit to-
ward the opposite wall must include a move-
ment of the rail B' or b laterally in its bed.
The rails, however, are when properly laid
substantially immovable in a lateral direction,
and hence the walls of the conduit securely
supported thereby. In order, however, to add
additional security to the permanency of the
walls of the conduits, the rails of each of the
tracks are tied together by bars O O', which
are securely fixed to the webs of the rails and
are embedded in the road-bed. This structure
renders it necessary to force both the rails lat-
erally in their beds in order to enable the walls
of the conduits to close and carry with them
the slot-irons to narrow the slot, and as such a
movement of the rails is substantially impos-
sible so long as the track is kept in order the
permanency of the slot of the desired width is
absolutely secured.

By arranging the ends of the ties I I' to abut
against the outer walls of the conduits their
position is further strengthened.

Access to the interior of the conduit may be
had by the removal of the paving-blocks in-
termediate of the conduits, handholds of any

well-known or approved form being arranged 30
in the walls of the conduits at suitable inter-
vals.

What I claim is—

1. The combination with a railway-track
and a conduit at the side and beyond the con- 35
fines of the track, the said conduit comprising
a bottom plate and side plates secured
thereto, of tie-plates of substantially the depth
of the web of the rail connecting one of the
side plates of the conduit with the web of the 40
rail adjacent thereto, whereby an extended
connection is formed between the said side
plate and rail, substantially as set forth.

2. The combination with a double track and
conduits located in the space between the in- 45
ner rails of the two tracks each of said con-
duits comprising a bottom plate and side
plates secured rigidly thereto, of deep tie-
plates connecting the adjacent side plates of
the conduits and tie-plates substantially the 50
depth of the webs of the rails connecting the
outer side plates of the conduits with the webs
of the inner rails of the two tracks, substan-
tially as set forth.

JOHN H. ROBERTSON.
